UNITED STATES PATENT OFFICE.

JULIAN T. GRZYBOWSKI, OF GRAND RAPIDS, MICHIGAN, ASSIGNOR OF ONE-HALF TO R. E. BUTTERWORTH AND JAMES LOWE, OF SAME PLACE.

MACHINE FOR GROOVING LUMBER.

SPECIFICATION forming part of Letters Patent No. 402,521, dated April 30, 1889.

Application filed November 1, 1887. Serial No. 253,989. (No model.)

To all whom it may concern:

Be it known that I, JULIAN T. GRZYBOWSKI, a citizen of the United States, residing at Grand Rapids, in the county of Kent and 5 State of Michigan, have invented a new and useful Improvement in Machines for Grooving Lumber, of which the following is a specification.

My invention relates to an improvement in 10 machines for grooving lumber; and it consists in the peculiar construction and combination of devices, that will be more fully set forth hereinafter, and particularly pointed out in the claims.

15 In the accompanying drawings, Figure 1 is a side elevation of a grooving-machine embodying my improvement. Fig. 2 is an end elevation of the same. Fig. 3 is a top plan view. Fig. 4 is a vertical longitudinal sectional view taken on the line $x-x$ of Fig. 3. Fig. 5 is a vertical transverse sectional view taken on the line $y-y$ of Fig. 3.

A represents a table which is rectangular in shape, and is provided at its four corners 25 with depending posts B, the said posts being made of metal and preferably circular in cross-section. From the center of the said table depends a similar post, C, which is provided on one side with a series of rack-teeth, D.

30 E represents a pair of cross-timbers which form a supporting-base. From the ends of these timbers extend supporting-legs F, which are made of cast metal inclined inwardly toward each other, and are provided at their upper ends with vertical cylindrical sockets G, adapted to receive the lower ends of the posts B. Set-screws H extend through the sides of the sockets and are adapted to impinge against the posts therein, so as to 40 clamp the posts securely thereto at any desired elevation, and thus support the table at any desired height. From the center of the crossed timbers projects a vertical standard, I, provided with a central opening adapted to

45 receive the lower end of the central post, C. In one side of the said standard is a vertical slot, K, which registers with the rack D, and in the lower end of the said slot is pivoted a pawl, L, which engages one of the rack-teeth, 50 and thereby secures the post C at any desired

adjustment in the standard. Near the upper end of the standard I, in one side of the same, is formed a case, M, in which is journaled a pinion, N, that meshes with the rack D. One end of the shaft of the pinion projects beyond one end of the case, and is squared and adapted to fit a wrench or lever, O. By first loosening the set-screws H and disengaging the pawl from the rack-bar the pinion may be turned so as to raise or lower the central 60 post, C, and thereby raise or lower the table to the desired adjustment, as will be readily understood. When the table has been thus adjusted, the set-screws H are caused to bind against the post D, and the pawl L is caused 65 to engage the rack-bar, and thereby maintain the table at the required adjustment.

It will be understood that the crossed timbers F form a movable supporting-base for the machine, whereby the machine can be 70 more readily moved to and set up in another place, or moved into or out of co-operative position with respect to a planer or other machine. The standard and legs are rigidly and 75 permanently secured to this base, and thus the latter serves to maintain the legs and the standard in their correct relative positions, and prevents any of the legs or the standard from getting displaced and caused to bind on the depending posts of the table. 80

In the ends of the table A are made vertical notches P, which are arranged near the corners thereof, and the said table is also provided with a series of three transverse slots, R, one of which is made in the center of the table, 85 and the others are made near the ends of the table, the said slots being parallel with each other. On the under side of the table are grooves S, which are arranged under the slots R and communicate therewith. 90

T represents a series of vertical bearing posts, which are provided at their lower ends with horizontal depending stems V, the upper portions of which are squared and are adapted to fit snugly between the sides of the slots R, 95 so as to prevent the stems from turning in the said slots. The lower ends of the said stems are screw-threaded, as shown.

U represents horizontal base-plates which bear upon the upper side of the table, are 100

provided with squared openings through which the posts T extend, and in which the said posts are adapted to move in a vertical direction. The said plates are further provided with square vertical openings, which are arranged on the sides of the posts.

W represents bolts which have enlarged heads at their lower ends that fit in grooves S. The upper portions of the said stems pass through vertical openings made in the base-plates U, and are provided with clamping-nuts X, which secure the base-plates firmly to the table and arrange the posts rigidly at the ends of the slots R. By loosening the nuts X the posts may be moved toward or from each other in the slots, and thus adjusted to any desired extent. In the upper end of each post T is made a horizontal transverse opening, through which extends a bolt, Y. The inner ends of the stems of the said bolts are circular in form and form the bearing-spindles for rollers Z. The outer ends of the said bolts are provided with screw-threads and nuts A', which screw onto them and serve to secure the bolts firmly in place.

B' represents coiled extensible springs which are arranged on the depending stems V of the bearing-posts, and nuts C' are screwed onto the said stems V and bear against the lower ends of the said springs, so as to cause the latter to normally move the rollers Z downward to within a suitable distance of the table-top.

D' represents a pair of vertical yoke-hangers, which have their upper ends bifurcated to form diverging arms, and are provided with vertical slots E' of suitable length. From the lower ends of the said yoke-hangers, on the inner sides thereof, project lugs F', which extend horizontally under the table. The said yoke-hangers D' have their vertical portions arranged in the notches P of the table, which are diagonally opposite each other. From the said notches, and formed integral with the table, depend guide-boxes G'. Bolts H', which serve to maintain the yoke-hangers, have their inner ends screwed into threaded openings in the inner sides of the guide-boxes G', and vertical bolts I' extend upward through openings in the lugs F' and engage vertical threaded openings in the lower ends of the inner sides of the said guide-boxes. The said bolts I' enable the yoke-hangers to be adjusted vertically to any desired extent, and the said bolts H' enable the yoke-hangers to be secured against movement at any desired adjustment. From the notches P', which are directly opposite the notches P in the table, depend guide-boxes K', which are similar to the boxes G'.

L' represents a pair of vertical yoke-hangers, which are similar in construction to the yoke-hangers D', but are somewhat longer than the latter, and have their lower portions fitted in the guide-boxes K', and are thus arranged directly opposite the hangers D'. Bolts M' pass through the vertical slots in the hang-

ers L' and engage threaded openings in the boxes K', so as to retain the said hangers L' at any desired vertical adjustment, and vertical bolts N' pass upward through openings in the lugs at the lower ends of hangers L' and engage threaded openings in the lower ends of the guide-boxes K' and serve to adjust the said hangers L' vertically. Between the arms at the upper ends of the hangers D' are pivoted bearing-boxes O', and between the diverging arms at the upper ends of the yoke-hangers L' are pivoted similar bearing-boxes, R'. The said bearing-boxes O' and R' are each made of a pair of semi-cylindrical pieces bolted together, as shown, provided with projecting trunnions which form their axes.

S' represents a pair of shafts, which are journaled in the bearing-boxes O' and R', and are arranged at a suitable angle with relation to the table, as shown, the said shafts being inclined in opposite directions. The lower end of each shaft S' extends a slight distance beyond the lower bearing, O', in which it is journaled, and is provided with a belt-pulley, T'. These portions of the shaft S' which are adjacent to the inner ends of the bearing-boxes are provided with screw-threads, as shown. A collar, U', is screwed to each shaft S', and is caused to bear against the upper end of its lower bearing, O', in order to prevent the shaft from moving longitudinally in its bearings, and the said collar U' is provided with a set-screw, V', by means of which it is prevented from turning on the shaft after the latter has been arranged at the correct adjustment. A series of cutter-heads, W', is placed on shaft S', the said cutter-heads being gradually enlarged as they approach the upper portions of the shafts, so that the lower edges of the cutter-heads will be arranged in the same horizontal plane above the top of the table A. Collars X' are placed on the shafts S', and are interposed between the cutter-heads, so as to separate the latter to the desired extent, and a sleeve-nut, Y', is screwed on the upper portion of each shaft S' and caused to bear against the largest cutting-head thereon, so as to bind the cutter-heads and the collars X' tightly together and cause them to rotate with the shafts S' when the same are turned. Saws or cutters of suitable construction are adapted to be secured to the shafts S' and are arranged in the same inclined plane therewith. Inasmuch as the shafts S' incline in opposite directions, the saws or cutters which are secured thereto are also caused to incline in opposite directions, and consequently the saws or cutters attached to the said shafts S' are caused to cut the opposite sides of dovetailed grooves in boards as the same are fed across the table A and under the rollers Z.

In the front and rear sides of the table A, at the corners thereof, are formed vertical guides or boxes a, in which are secured vertical standards b by means of bolts c, which

pass through vertical slots in the said standards and enter threaded openings in the boxes. To the ends of these standards *b* are journaled rollers *e*.

5 In practice my grooving-machine is employed in connection with a planing or matching machine, and as each board is moved from the planing or matching machine it is fed to the grooving-machine, and is guided by the 10 rollers *Z* and the inner edges of the bases *U* under the revolving cutter-heads, so that the saws or cutters thereof form dovetailed grooves in the upper side of the board, as will be very readily understood.

15 The posts *T* are laterally adjustable toward and from each other, so as to adapt the machine to groove boards of varying widths, and the springs *B'*, which bear downward on the posts *T*, keep the rollers *Z* and bear firmly on 20 the upper sides of the boards, so as to prevent the latter from rising while being operated upon by the saws or cutters, and consequently causing the grooves formed in the said boards to be of a uniform depth.

25 The grooving-machine may be operated by belts which extend directly from pulleys on a counter-shaft in the planing or matching machine to the pulleys *T'* on the shafts *S'*; or 30 connecting its pulleys *T'* with suitable pulleys secured to the inclined knuckle-jointed ends of a counter-shaft suspended from the ceiling above the machine. Other means may be employed for imparting motion to the operating 35 parts of my grooving-machine, as will be readily understood, as I do not limit myself in this particular.

It is sometimes desirable to let the boards as they come from the planing or matching 40 machine pass over the grooving-machine without being grooved thereby. In order to accomplish this result, I lower the bed or table *A* to a plane somewhat below that of the planing or matching machine, and also lower 45 the cutters by lowering the standards or bearings in which their shafts are journaled, and move the standards *b* upward a sufficient distance to elevate the rollers *e* to a plane above the upper edges of the revolving cutters, said 50 standards being long enough for this purpose. When thus arranged, the boards as they come from the planing or matching machine are caused to bear upon the rollers *e*, and are directed thereby over the cutters and out of 55 contact therewith, and consequently the boards pass over the grooving-machine without being grooved.

Having thus described my invention, I claim—

60 1. In a grooving-machine, the combination, with the bed or table having the vertical notches in its sides, of the vertical standards fitting in said notches and having the vertical slots and the inwardly-extending lugs *F'* at their lower ends, the vertical adjusting-screws extending through the lugs and engaging threaded openings in the lower side of the ta-

ble, and clamping-bolts extending transversely through the slots in the standards and engaging threaded openings in the sides of the table, 70 the bearings *R' O'*, pivoted in the upper ends of the standards, and the oppositely-inclined shafts journaled in said pivoted bearings and having the cutter-heads, substantially as described.

75 2. In a grooving-machine, the combination of the movable base, the hollow central standard, *I*, and the legs *F*, arranged around the standard, all resting on and permanently and rigidly secured to the base, said legs *F* being 80 solid and having at their upper ends cylindrical sockets or sleeves *G*, open at both ends, the bed-plate or table having the cylindrical posts *B*, to work through the sleeves *G*, and the post *C*, to work into the standard *I*, the 85 set-screws for the sleeves *G*, the rack on the post *C*, the pinion journaled in the standard *I* and engaging the rack, and the pawl, also engaging the rack, as set forth.

90 3. The combination of the movable supporting-base, the vertical standard *I*, resting on and permanently secured to the center of the base, the legs *F*, arranged around the leg *I* and resting and permanently secured on the base, whereby said legs or standards *I* and *F* 95 are rigidly connected, the sockets or sleeves *G* at the upper ends of legs *F*, the bed-plate or table having the depending posts *B* extending through and working in the sockets or sleeves, and the depending post *C*, working 100 in the standard *I* and having the rack and the pinion journaled on the standard *I* and engaging the rack to lift or lower the bed-plate or table, substantially as described.

105 4. The combination of the crossed timbers *E*, forming the supporting-base, the standard *I*, having its lower end bolted on the center of the base, the legs *F*, having their lower ends secured on the ends of the crossed timbers and provided at their upper ends with 110 the sockets or sleeves *G*, the table or bed-plate having the central depending post, *C*, working in standard *I*, and the depending corner-posts *B*, working in the sockets or sleeves, and means, substantially as set forth, 115 to lift and lower the bed-plate or table, substantially as described.

120 5. The combination, in a grooving-machine, of the bed-plate or table having the slots *R*, the laterally-adjustable posts *T*, having the 125 stems extending through the said slots and depending from the table or plate, said posts being adjustable independently of each other, the rollers *Z*, journaled to the said posts, and the springs bearing downward on the said posts, for the purpose set forth, substantially as described.

130 6. The combination, in a grooving-machine, of the bed-plate or table having the slots *R* and the grooves *S* on its under side and communicating with said slots, the laterally-movable posts *T*, having the depending studs fitted in the slots, the rollers *Z*, journaled to the said posts, the base-plates *U*, bearing on the

- bed-plate or table, having the openings to receive the lower ends of the posts, and the bolts *W*, having their heads fitted in the grooves *S*, the said bolts extending upward 5 through the slots *R* and through the openings in the base-plate, and provided with clamping-nuts *X*, bearing on the upper side of the base-plate, for the purpose set forth, substantially as described.
- 10 7. In a grooving-machine, the table or bed-plate, the hangers or standards having the slots *E'* and provided with the lugs *F'*, which engage under the table, the bolts extending through the slots *E'* and entering the table 15 or bed-plate, and thereby securing the hangers thereto, the bearing-boxes pivoted to the said hangers or standards, and the oppositely-inclined shafts journaled in the said bearing-boxes and having the cutter-heads, substantially as described.
- 15 8. In a grooving-machine, the table or bed-plate having the guide-boxes *G'*, the hangers or standards having their upper ends bifurcated to form diverging arms and having 20 the slots *E'* and provided with the lugs *F'*, which engage under the table, the adjusting-screws *I'*, extending through the said lugs and engaging the guide-boxes, the bolts extending through the slots *E'* and entering the guide- 25 boxes, and bearing-boxes pivoted to said hangers or standard, and the oppositely-inclined shafts journaled in the said bearing-boxes
- 30

and having the cutter-heads, substantially as described.

9. The combination, in a grooving-machine, 35 of the vertically-adjustable bed-plate, the grooving mechanism supported above the bed-plate and vertically adjustable, and the vertically-adjustable standards *b*, secured to the bed-plate and having the rollers *e* at their 40 upper ends, whereby, when the bed and grooving mechanism are lowered and the standard raised, the rollers serve to direct the board over the grooving mechanism, substantially as described.

45 10. The combination, in a grooving-machine, of the bed-plate or table having the vertical guide-boxes formed in its sides, the vertically-adjustable hangers or standards secured in the guiding-boxes and having the lugs *F'*, 50 the adjusting-screws *I'*, extending through the said lugs and engaging the lower ends of the guiding-boxes, the bearing-boxes pivoted to the said standards or hangers, and the oppositely-inclined shafts journaled in said 55 bearings and having the cutter-heads, substantially as described.

In testimony that I claim the foregoing as my own I have hereto affixed my signature in presence of two witnesses.

JULIAN T. GRZYBOWSKI.
